(57) **CLAIM**

The ornamental design for a yoga wheel, as shown and described.

DESCRIPTION

FIG. 1 is a front, right and top perspective view of a yoga wheel showing my design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof; and,

FIG. 8 is an enlarged view of a portion indicated in FIG. 1. The broken lines are included for the purposes of illustrating portions of the yoga wheel that form no part of the claimed design. The uneven dot-dash broken lines encircling portions of the yoga wheel in FIG. 1 and illustrated in enlarged view in FIG. 8 form no part of the claimed design.
